HARRY C. ISBELL, OF CHICAGO, ILLINOIS

SLING

Application filed December 16, 1929. Serial No. 414,484.

These improvements relate to slings for throwing objects by hand. Broadly considered the device is of great antiquity.

I have devised a certain sling game in which both the distance and the accuracy of the ball's projection are important factors. From much practice and experimentation I have found that with the ordinary sling, in which the ball is held in a hole in the leather, or in which there is any form of pocket-like receptacle for the ball, certain counteracting influences prevent the ball from leaving the sling with the desired freedom, and both the direction and force of throw are thereby modified. The conditions making for aberrations from expected results are of such nature that the thrower cannot provide for them by allowances. For example, if the ball or the leather be wet, as in the case of rain or the presence of dew, the old form of sling body takes a peculiar grip upon the ball at certain portions thereof and the deflection from the expected line of throw is very marked, and with loss of distance. Various degrees of humidity of the atmosphere have corresponding effects. Oiling the leather to keep or make it supple changes the results in various ways. Slight differences in construction or material make for noticeable variations from the properly-to-be expected character of throw. In short, with the old-time type of sling the thrower can not control his delivery as desired.

Under these circumstances I sought to ascertain the cause or causes of the trouble, and with the result of overcoming all of the objections referred to by providing a sling according to this specification, by which the ball may be satisfactorily projected, and with all of the force and trueness of direction to which entitled by the strength and skill of the thrower.

In the drawings Figure 1 is a perspective of my novel sling complete, except that the swinging cords are partly broken away;

Fig. 2 is a fragmentary top view of the body laid out straight with one end extension broken away;

Fig. 3 shows the device of Figs. 1 and 2 chiefly in medial vertical section but with

one of the cord-holding extensions in full side view;

Fig. 4 is a transverse sectional view as on the line 4—4 of Fig. 3;

Figs. 5 and 6 are fragmentary top views 55 similar to Fig. 2 showing modifications in the ball-seat construction; and

Fig. 7 is a view similar to Fig. 3 showing a modification of the body construction.

Turning to Fig. 1, the sling is seen to contain broadly the elements of a body and the swinging cords or thongs of the ordinary sling. In use the ball 12 held by the body is retained by centrifugal force as the device is swung until one of the cords, as 10, is released, 65 when the ball is discharged.

A minor feature of improvement shown in Fig. 1 is in the loop device at the free end of cord or thong 11. There is a soft elongated flexible element 50, leather in my practice, apertured at 51 to receive loosely the cord or thong 11 which is made fast to the opposite end of the element 50, as by aperturing the member 50 at 52 and applying a button or knot 53 at the free end of the cord. This 75 construction enables the operator to slip say his third finger into the space marked 54 and then passing the cord over the second finger of the same hand so that when the cord 10 is held between the first finger and the thumb of that hand both of the cords 10 and 11 are definitely under the control of the operator's fingers and thumb in making the throw. The act of applying the cord 11 firmly and securely to the hand is thus rendered simple 80 and convenient, and there are advantages, too, in the better sense of "feel" and control provided.

The principal improvements hereof are in connection with the sling body, which is marked A in Figs. 1 to 4. These improvements may be described first with respect to the base of that body.

It will be observed that in the preferred form of Figs. 1 to 4 the base marked as a 95 whole B is substantially flat adjacent to the ball, and in this respect, so far as I know, it distinguishes from all other slings of this character.

The various bases illustrated are shown as 100

being substantially flat as a whole, but this shape is to be understood as resulting from the kinds of material used in a construction which makes for convenience in manufacture, lightness and the desired strength. The principal feature sought to be expressed in the flat construction is the freedom of the body as a whole from a pocket-like formation adjacent to where the ball is seated. 5 Note in Fig. 3 that there are large open spaces marked S between the body and the ball. In the old type of sling the ball is hugged tightly, or in the discharge areas will be contacted by, the "leather" at the ball. 10 areas facing these spaces S. I desire to avoid all such contacts. The flat construction illustrated and as is hereinafter more particularly described, provides the desired advantages in this respect, but it will be clear that 15 the shape of the bottom is of no particular importance and that various other modifications in construction may be made while still providing the desired freedom of the ball from such laterally contacting or impinging 20 areas on the body of the sling. 25

Other characteristics of the base B are that it is so substantially strong and stiff that it maintains its desired shape, especially as to the upper parts thereof, under the very considerable centrifugal forces tending to form it pocket-like during the swinging operation. 30

Turning to Fig. 3 the body comprises the base B and the extensions C and D from what may be termed the ends of the base. These 35 end extensions should be of some such strong and flexible material as leather. They form means for securing the swinging elements as 10 and 11 to the body, and, as shown in Fig. 3 the upper portions of the extensions C and D are folded around the cords 10 and 11 at 14 and 15 and windings of cord or wire 40 16 and 17 bind the cords 10 and 11 tightly. I preferably add a bulbous element at the free ends of the respective cords to prevent 45 the possibility of their slippage through, and in the figures shown I have indicated balls 18 and 19 for this purpose, which in my practice, are ornamental beads and are held by enlarging windings 20 and 21 at the exposed ends of the cord. 50

The end extensions C and D are integral with the base element 22 which, as shown in Fig. 2, is widened out laterally, in which respect it is similar to the old sling well known. 55 The base part 22, being of soft leather, would not maintain its desired shape. I therefore provide a second base element 23, which is shown in the form of a plate-like piece of strong, stiff and quite rigid material. Sole leather is suitable for the purpose. It is 60 stitched at 24 to the base element 22, and these two laminations combined form a rigid yet springy structure adapted to maintain the desired shape for some time, but that construction alone is not deemed by me sufficient 65

to provide the desired rigidity for long life and service. The part 23 could be of stiffer material than leather, for example hard rubber, or even metal.

On the top surface of base member 22 I 70 provide two guide members 25 and 26, which in my practice are also of leather strongly stitched at 27 to the base member 22. These elements 25 and 26 further strengthen the construction to maintain a substantially flat condition of at least these parts 25 and 26. 75 Figs. 2 and 4 show that the guides 25 and 26 are spaced apart and are provided with downwardly-and-inwardly slanting surfaces 25^a and 26^a, against which the ball 12 rests. 80 As shown in Fig. 2 the ball may roll freely on these guides toward the extensions C and D while being retained against lateral movements. It will be observed that these guideways 25^a and 26^a do not form in any sense a pocket, and that especially they do not form a pocket in the direction of the extensions C and D. The more rigid element 23 extends sufficiently toward the extensions C and D to maintain the spaces as S. 85

In order to provide a base which will not become distorted and form a pocket-like condition where leather or the like is used I have added a third reinforcing element in the form of a thin plate 30 (Figs. 3 and 4) of fiber, which material is not only stiff but it is also springy. A metal plate could be used in the same position. 90

The base thus far described, while being strong and well adapted to maintain its desired shape under conditions of use, is formed also to provide a slight yield in the outward direction under the centrifugal weight of the ball, putting the several parts of the base under spring tension. At the moment of release in the throw this stored-up energy becomes effective to separate the ball and the body of the sling practically instantly. The desideratum is to release the ball instantly the operator releases the cord as 10. If the ball be not thus instantly released its direction will be interfered with and the full effect of the power applied will not be had. 100

Turning to Fig. 2 it will be observed that while the extensions C and D are in holding relation to the ball, the ball is not being contacted at any other place than high up at the sides and at narrow opposite lines in the guides of the base. The natural tendency of the extensions C and D is to spring apart 105 when the swinging pressure is released and then, since there is no part of the device in gripping relation to the ball, the ball flies away true to the force and skill applied. 110

Turning to Fig. 7, in which like parts will be given, the same reference characters as in Fig. 3, the modification is in the provision of integral end extensions of the base element 23^a to form the reinforcing elements E which extend well up along the sides of extensions 115 120 125 130

C and D, and the cords 10 and 11 are secured to the elements E by passing them through holes 35 whereby the locking elements as 18 and 19 hold the wing-like parts E in close relation to members C and D. This integral member 23^a and EE is of leather of substantially the kind used for members 23^a, C and D. The parts are stitched together at 36, and the plate 30 between the laminations may be of such material as to provide the desired strength and rigidity, preferably coupled with the slight springiness hereinabove pointed out. The construction of Fig. 7 is peculiarly strong and serviceable, the parts taking the principal strains being of double thickness.

Turning to Fig. 5, a part corresponding in various respects to element 25 is marked 40 and the same is strongly stitched to the base 22^a corresponding in all respects to the base part 22 of Fig. 3. Instead of having guides providing that the ball may roll freely in both directions there are stop means at one end, and, as illustrated, the downwardly slanting guide surfaces 41 terminate in a curved seat at 42. The open end of the guides 41 is toward extension C, which, as will be seen from Fig. 1, is associated with cord 10, namely, the cord to be released. The ball may therefore roll freely away from the seat part 42 at the instant of release. The tendency of the sling body is to grip the ball chiefly on the side thereof to which the releasable cord 10 is secured, and I desire particularly to avoid all counteracting contacts on that side. The modification of Fig. 5 therefore provides for the desired freedom in the release from the side of the body chiefly involved. Parts not illustrated in Fig. 5 and not specifically described may be considered to be in accordance with the preferred form except as to the plate-like piece 40.

In Fig. 6 the plate-like piece 45 has a downwardly and inwardly slanting circular seat 46 and departs only in this respect from the preferred form. In the use of the device of Fig. 6 it will be found that an indentation of the leather 45 is formed at 47, showing that at the instant of release the part at 47 is obstructive, and this is on the side of releasable cord 10. In this respect the device of Fig. 6 is not as satisfactory as those of the other illustrations; but a sling constructed in accordance with Fig. 6 would be greatly superior to one built along the old lines in which the ball is pocketed and contacted at areas facing the spaces S in Figs. 3 and 7. The grip upon the ball at the small area 47, while being of the kind which I desire to avoid, is relatively slight, and even this may be avoided by a greater resiliency in the base than I would ordinarily employ in connection with the other devices shown.

Such slings are ordinarily used with a swinging overhead motion in a substantially

horizontal plane for best directional effects with good distance, with a sort of diagonal motion having both vertical and horizontal components for the greatest distance, and with a sidewise motion in a vertical plane for short pitching-like throws. The wrist is turned during the swinging movement so as to preserve the cords as 10 and 11 parallel with each other in a general sense, to prevent their becoming twisted. The use of such slings is generally understood, and the desired skill is a matter for practice.

I may mention that a loaded guttapercha ball weighing from two to five ounces is suitable for accurate throwing and good distance. While stones and other irregular objects could be thrown to advantage in the present sling, my chief object is to provide an appropriate sling for use in a game to be played over a course or courses laid out in an open field, and I therefore suggest a ball as the most suitable missile, with the sling body particularly adapted to the use of a spherical object.

I contemplate as being included in these improvements all such changes, variations, departures and modifications from what is thus specifically illustrated and described as fall within the scope of the appended claims.

I claim:

1. A sling of the character described comprising a body and opposite end extensions therefrom for cord or thong attachments, the body having a base formed to seat a missile thereon with the missile free of contact with at least one of said extensions at areas near the base when the device and missile therein are normally being swung.

2. A sling of the character described comprising a body and opposite end extensions therefrom for cord or thong attachments, the body having a base formed to seat a missile thereon with the missile free of contact with said extensions at areas near the base when the device and missile therein are normally being swung.

3. A sling of the character described having a body comprising an integral strap-like member of flexible material having a base portion and extensions at opposite ends of the base portion for cord or thong attachments, there being a substantially stiff reinforcing member secured to said base portion and adapted to cooperate therewith in maintaining the base as a whole in a substantially constant shape.

4. A sling of the character described having a body which includes a base and flexible end extensions, the base being but slightly flexible, if flexible to any extent, between said end extensions.

5. A sling of the character described having a body which includes a base and flexible end extensions, the base being but slightly flexible, if flexible to any extent, between

said end extensions, there being seat means for a missile on the base, the construction providing that the missile is free of contact with said end extensions at any place closely adjacent to the base when the sling and missile are normally being swung.

6. A sling of the character described which includes a body having a substantially flat, strong and stiff base.

10. 7. A sling of the character described which includes a body having a base formed of laminations, the base being strong and stiff and adapted to maintain itself in a substantially constant shape under all conditions of use.

15. 8. A sling of the character described which includes a body having a laminated base, one lamination thereof being of flexible material and extending away from the base at opposite ends thereof, another lamination thereof being of stiff material adapted to maintain the upper portion of the base substantially flat under conditions of use.

20. 9. A sling of the character described which includes a substantially flat base formed of laminations, one of said laminations consisting of a plate-like piece of strong, stiff and springy material.

25. 10. A sling of the character described which includes a body having a base which is substantially flat as to its upper portion, with means associated with the base adapted to be put under spring tension when the sling is loaded and being swung preparatory 30 to a normal throw.

11. A sling of the character described which includes a body having a base formed of laminations, one lamination being of flexible leather or the like, another lamination being a piece of strong and stiff material.

20. 12. A sling of the character described which includes a body having a base formed of laminations, one lamination being of flexible leather or the like, another lamination being a piece of strong and stiff material, with seat means for a missile carried by the inner one of said laminations.

25. 13. A sling of the character described which includes a body having a base substantially free of pocket-like characteristics.

14. A sling of the character described which includes a body having a base with a seat thereon substantially free of pocket-like characteristics.

25. 15. A sling of the character described which includes a body having a base provided with means for holding a ball substantially free of contacts between the base and the ball which are in lines transverse to the line of throw at the instant the ball is released from the sling in a normal throw.

16. A sling of the character described which includes a base and lateral extensions therefrom adapted for securing cords or the like thereto respectively, the base including

means adapted to hold a ball substantially free of contact with one of said extensions adjacent to the base at the instant of release of the ball in a normal throw.

17. A sling of the character described which includes a body having a base and extensions therefrom for securing cords or the like thereto respectively, the base having means providing spaced apart guides substantially parallel with each other and directed toward said extensions respectively, said guides being adapted to hold a ball for free rolling movements toward at least one of the extensions while maintaining the ball against movements relative to the base in directions at right angles to the directions of the guides when the device is normally in use.

18. A sling of the character described comprising a body having a substantially flat, stiff and strong base with extensions therefrom for the attachment of cords or the like respectively, a pair of guides upstanding from the base, the guides having oppositely-disposed downwardly-and-inwardly inclined track surfaces parallel with each other and directed longitudinally toward said extensions respectively.

19. A sling of the character described comprising a body having a base with flexible sheet-material extensions at opposite ends thereof, and a cord or the like secured to each of said extensions, the extensions substantially enveloping the cords respectively at portions of the extensions respectively, with a winding around each extension at the place of the cord therein to bind the extension and the cord tightly together.

20. A sling of the character described having a body and a pair of swinging cords or the like, one of said cords having anchoring means comprising a short, flexible plate-like element apertured at one end, with the cord passing loosely through said aperture, the end of the cord being secured to the opposite end of said element to provide an adjustable loop for the finger of the operator, one part of the loop being said element and the other part thereof being the cord or the like.
